(57) **CLAIM**

The ornamental design for a device for aesthetic treatment of the body, as shown and described.

DESCRIPTION

FIG. 1 is a front right perspective view of a device for aesthetic treatment of the body showing my new design; FIG. 2 is a right side view thereof;

FIG. 3 is a left side view thereof;

FIG. 4 is a front view thereof;

FIG. 5 is a top view thereof;

FIG. 6 is a bottom view thereof;

FIG. 7 is a rear view thereof; and,

FIG. 8 is a bottom left perspective view thereof.

The broken lines shown illustrate portions of the device for aesthetic treatment of the body, which form no part of the claimed design.
